UNITED STATES PATENT OFFICE.

WILLIAM HENRY ELMOND, OF KANSAS CITY, MISSOURI, ASSIGNOR OF ONE-HALF TO MARTIN A. PENINGTON, OF SAME PLACE.

RAIL-BRAKE.

SPECIFICATION forming part of Letters Patent No. 448,419, dated March 17, 1891.

Application filed December 9, 1890. Serial No. 374,008. (No model.)

To all whom it may concern:

Be it known that I, WILLIAM HENRY ELMOND, a citizen of the United States, residing at Kansas City, in the county of Jackson and

5 State of Missouri, have invented certain new and useful Improvements in Rail-Brakes; and I do hereby declare the following to be a full, clear, and exact description of the invention, such as will enable others skilled in the art 10 to which it appertains to make and use the same.

My invention relates to improvements in rail-brakes adapted for use on cable and other cars; and the primary object of the invention 15 is to provide a brake the sole of which is detachably secured within and connected to the brake-shoe, so as to permit of its ready removal and replacement by another sole when desirable.

20 A further object of the invention is to provide a brake the sole of which can be adjusted vertically with relation to the brake-shoe in order to compensate for wear on the contact-face of the sole.

25 A further object of the invention is to provide a clamp or locking device for securing the sole in position in the brake-shoe, which can be easily operated without the aid of any tool to release the sole when desired.

30 A still further object of the invention is to provide a rail-brake which shall be cheaper of manufacture, as efficient in operation, and much simpler in construction than any device of this kind known to me and at present 35 in use.

With these and other ends in view my invention resides in the combination of an angular brake-shoe adapted to partially surround a wooden sole and provided near either 40 end with an upwardly-extending lug, a clamping or locking plate connected to the outer face of each of said lugs, and an operating-lever fulcrumed or pivoted in each of said lugs and operating between the outer face of 45 the lug and the inner face of the upper portion of the clamping or locking plate to force the lower edge of said plate tightly against the outer face of the sole of the brake and hold it securely in position within the brake-shoe.

My invention further resides in the peculiar construction and arrangement of parts, as will be hereinafter more fully described and claimed.

In order that others may understand my invention, I have illustrated the same in the accompanying drawings, in which—

Figure I is a perspective view of a brake-shoe detached from the car constructed in accordance with my invention. Fig. II is a 55 transverse sectional view on the line $x-x$ of Fig. I. Fig. III is a side elevation showing the manner of compensating for wear on the contact-face of the sole of the brake; and Fig. IV is a side elevation showing the parts 60 in position to allow of the removal of the sole 65 of the brake-shoe.

Like letters of reference denote corresponding parts in all the figures of the drawings, referring to which—

70 A designates the brake-shoe, of iron or any other suitable material, substantially right-angled in cross-section, and the shoe partially incloses the brake-sole B, which preferably consists of a block of wood, which material has by practice been proved the most effective material for this purpose. The brake-shoe A has each end partially closed by a piece C, made integral with the shoe, and these end pieces C serve to prevent endwise movement of the sole B within the shoe when the same is forced into contact with the rail to stop the motion of the car; and the shoe A is further provided on its upper side near 75 either end thereof with an upwardly-extending lug D, one face of the lug D being flush with the outer face of the top of the shoe A.

Through the lug D passes a short bolt E, and on this bolt is fitted a clamping or locking plate F, made of any suitable material and 80 extending from a point some distance above the bolt E to a point about on line with the lower edge of the rear and end pieces of the brake-shoe A. The plate F is held on the bolt E by means of a nut G, and the lower edge of 85 said plate is bent inwardly to form a tooth or biting-edge H, which is adapted to take or be forced into the outer face of the sole B for the purpose of holding the same in position 90 in the brake-shoe. In the outer face of the 95

lug D, near the inner end thereof, is pivoted a wedge-like lever K, which operates between the outer face of the lug D and the inner face of the clamp or plate F, said plate having its upper end grooved or recessed in order to form a socket L for the reception of the lever K. The lever K is of such proportions and shape that when it is in position between the lug and the plate, as shown in Figs. I and III, it operates to force the upper end of the plate F outward a slight distance, and as said plate is prevented from rearward movement on the bolt E by the nut G this outward movement of the upper end causes the lower end of the clamping-plate to be moved inward toward the outer face of the brake-sole and thus force the tooth or biting-edge H firmly therein.

In Fig. IV of the drawings I have illustrated means for compensating for the wear on the lower or contact face of the brake-sole B, which very desirable end I accomplish in the following manner: When the lower or contact face of the brake-sole has become worn, so as to avoid contact with the rail when the brake-shoe is depressed, the lever K is raised, which relieves the pressure on the upper end of the plate F, and the biting-edge H can be withdrawn from the face of the brake-sole by slightly pressing on the plate. The brake-sole is then lowered the required distance and a filler or strip of wood M of the necessary thickness is forced or wedged between the upper surface of the brake-sole and the inner surface of the brake-shoe to completely fill the space formed by lowering the brake-sole. The lever K is then depressed again and the lower biting-edge of the clamping-plate forced into the brake-sole. It is obvious that the brake-sole can be lowered from time to time as it becomes necessary, so long as the upper edge of the brake-sole remains above the line of the biting-edge of the clamp F and the lower edge of the rear and end pieces of the brake-shoe. When the brake-sole becomes worn to such an extent that it is impossible to lower it, in the manner just described, sufficiently to make it effective, or for any other reason it is desired to replace the old sole with a new one, the lever K is raised and the plate F turned on the bolt E into the position shown in Fig. IV, when the new sole can be readily fitted into the brake-shoe and locked therein in the manner hereinbefore described.

The operation and advantages of my invention will be readily understood and appreciated by those skilled in the art to which it relates from the foregoing description, taken in connection with the accompanying drawings.

No means for attaching the brake-shoe to the body or frame of a car is here shown and described, as the same forms no part of my

invention. Any of the common forms of connections now in use may be used in connection with my improved brake-shoe.

I am aware that changes in the form and proportion of parts and details of construction can be made without departing from the spirit or sacrificing the advantages of my invention, and I therefore reserve the right to make such changes as fairly fall within the scope of my invention.

Having thus described my invention, what I claim as new, and desire to secure by Letters Patent, is—

1. In a rail-brake, the combination, with a brake-shoe and a brake-sole, of the locking-plates, and the wedging-levers operating between the brake-shoe and the locking-plates, substantially as described, for the purpose specified.

2. In a rail-brake, the combination of a brake-shoe provided with the lugs, a brake-sole, and the locking-plates connected to the lugs and engaging the brake-sole, substantially as shown and described.

3. In a rail-brake, the combination of a brake-shoe provided with the lugs, the brake-sole, the locking-plates detachably secured to the lugs and contacting at one end with the brake-sole, and the wedging-lever pivoted in the lug and operating between the lug and the clamping-plate, all combined and arranged as and for the purpose described.

4. In a rail-brake, the combination of a brake-shoe, the brake-sole fitted in the brake-shoe, the connecting-plates intermediate of the brake-shoe and the brake-sole and provided at one end with the tooth or biting-edge and at the other with a socket, and the wedging-levers pivoted on the brake-shoe and operating between the shoe and the plates, substantially as shown and described, for the purpose specified.

5. In a rail-brake, the combination, with an angular brake-shoe provided with the end pieces and the upwardly-extending lugs, of a brake-sole fitted within the brake-shoe, the bolts E, passing through the lugs of the brake-shoe, the locking-plates detachably fitted on said bolts and each provided at one end with the inwardly-extending biting-edge and at the other end with the socket L, and the wedging-levers pivoted in the lugs of the brake-shoe and operating between such lugs and the locking-plates, as and for the purpose specified, substantially as shown and described.

In testimony whereof I affix my signature in presence of two witnesses.

WILLIAM HENRY ELMOND.
